UNITED STATES PATENT OFFICE.

GENEVIEVE HEILNER, OF NEW YORK, N. Y.

CORSET.

1,317,623.

Specification of Letters Patent. Patented Sept. 30, 1919.

Application filed April 14, 1919. Serial No. 289,774.

To all whom it may concern:

Be it known that I, GENEVIEVE HEILNER, citizen of the United States, residing at New York city, in the county of New York 5 and State of New York, have invented certain new and useful Improvements in Corsets; and I do declare the following to be a full, clear, and exact description of the invention, such as will enable others skilled in 10 the art to which it appertains to make and use the same.

My invention has for its object to provide a corset constructed in a novel manner to reduce the abdomen and at the same time to 15 support the same in a comfortable manner, and in carrying out this end I provide the front of each half of the corset with two flaps which are secured along vertical lines to spaced portions of the usual fabric body, 20 the lower ends of said flaps being attached to each other and carrying hose supporters, while the upper portions of said flaps are preferably connected by elastic inserts. By this arrangement, the downward pull on the 25 hose supporters keeps the abdomen down in proper position, the connected lower ends of the two flaps comfortably support the same, and sufficient elasticity for comfort is allowed by the inserts.

30 With the foregoing in view, the invention resides in the novel association of parts shown in the drawing, described hereinafter, and particularly pointed out in the appended claims.

35 Figure 1 is a front elevation of a portion of a corset constructed in accordance with my invention.

Figs. 2 and 3 are respectively a vertical and a horizontal section on the planes indicated by the lines 2—2 and 3—3 of Fig. 1.

In the drawing above briefly described, the numerals 1 designate the two halves of the usual fabric body of the corset, said halves being provided at their front edges with 45 appropriate fasteners 2. Wherever required, stays 3 are provided and these stays may terminate a suitable distance below the bottom of the corset. The front edges of the halves 1 are by preference bound by fabric strips 4 and the lower ends of said edges 50 preferably carry hose supporters 5. Other supporters 6 are shown at points spaced outwardly from the supporters 5, and between the supporters 5 and 6, others 7 are located, 55 it being with these supporters that the present invention is concerned.

In the present arrangement, each half of the fabric body is formed of sections connected to each other by vertical rows of stitching 8 and one of these rows is located 60 approximately four inches from each row of stitching 9 by which the binding strips 4 are attached. I preferably use the two rows of stitching 8 and 9 for attaching the flaps 10 and 11 to the corset, but it is to be clearly 65 understood that this manner of connection is not essential and that any preferred means could be provided for attaching the flaps in the required manner.

The flaps 10 and 11 are shown of approximately triangular form, but here again this shape need not be followed too closely. It is essential however that the lower ends of the two flaps shall be secured one to the other, as by stitching 12, that only the remote outer edges 11^a of said flaps shall be attached to the corset, and that the supporters 7 be connected to said lower ends of the flaps. The upper ends of the flaps 10 and 11 75 diverge upwardly and an elastic insert 13 80 by preference connects said flaps near said upper ends. The insert is attached to the flaps by stitching or the like 14 and is free of connection with the fabric body of the corset, and said insert is of such length as to 85 slightly pucker said fabric body as seen at 15, before the corset is applied. When positioned snugly around the wearer's body however the pockers 15 are more or less drawn out and it will be seen that the inserts will 90 provide sufficient elasticity for comfort, allowing a slight expansion over the abdomen.

When the corset is applied, the four flaps 10 and 11 are positioned in front of the abdomen and their overlapping portions are so 95 disposed with relation thereto as to form an effective and comfortable support. The hose supporters 7 exert a downward pull on the flaps, consequently exerting a downward pressure on the abdomen which has a noticeable tendency to reduce the same. The elastic inserts 13 permit the necessary slight expansion over the abdomen, and render the corset extremely comfortable to the wearer, but it will be understood that it is possible 100 to omit these inserts in some forms of the device.

Since excellent results have been obtained from the exact construction and arrangement shown, they are preferably followed, but it is to be understood that I have 110 illustrated but one form of the device and

that it may be manufactured in numerous other embodiments within the scope of the invention as claimed.

I claim:

- 5 1. The combination with the front portions of two corset halves; of a pair of flaps stitched on approximately vertical lines to the outer side of each of said front portions and being otherwise free of connection with said 10 halves, said flaps depending from the lines of stitching to a common point, being connected to each other at said common point and mutually carrying a hose supporter at said point.
- 15 2. The combination with the front portions of two corset halves; of a pair of flaps stitched on approximately vertical lines to the outer side of each of said portions, said flaps depending from the lines of stitching

and being otherwise free of connection with 20 said halves, the lower ends of said flaps being overlapped, connected to each other, and carrying a hose supporter.

3. A structure as specified in claim 1, together with an elastic insert between and 25 attached at its ends to the upper portions of said flaps, said insert being of a length to slightly pucker the front portion of the corset halves.

4. A structure as specified in claim 2, together with an elastic insert between the upper portions of said flaps and of a length to 30 slightly pucker the front portion of the corset halves, said insert being attached at its ends to said flaps.

In testimony whereof I have hereunto set my hand.

GENEVIEVE HEILNER.
